UNITED STATES PATENT OFFICE.

ALBION P. BICKMORE, OF HYDE PARK, MASSACHUSETTS, ASSIGNOR OF
ONE-HALF TO EDWARD B. PENDLETON, OF SAME PLACE.

SELF-LEVELING BERTH.

SPECIFICATION forming part of Letters Patent No. 276,341, dated April 24, 1883.

Application filed May 3, 1882. Renewed March 5, 1883. (No model.)

To all whom it may concern:

Be it known that I, ALBION P. BICKMORE, of Hyde Park, in the county of Norfolk and State of Massachusetts, have invented a new and useful Improvement in Self - Leveling Berths; and I do hereby declare that the following is a full, clear, and exact description of the same.

My invention relates to an improvement in 10 swinging or self-leveling berths, intended especially for use on steam and sailing vessels.

In an application filed by me in the Patent Office January 24, 1882, I described an improved construction of single swinging berth 15 suspended from a frame by a peculiar universal joint and anti-friction bearing.

My present invention is applicable to double or upper and lower berths; and its object is to provide an upper and lower berth suspended 20 from a common support, so as to have a simultaneous movement in one direction, with supporting-frame, and a separate movement laterally independent of the frame, one of the berths being placed above and one below the 25 common point of support and balanced in that position.

The invention consists in the construction and arrangement of the devices necessary to carry out this object, and, further, in a peculiar canopy or curtain for shutting off the berths from observation, either together or separately.

In the drawings, Figure 1 represents a perspective of the interior of a state-room containing an upper and lower berth constructed 35 in accordance with my invention; Fig. 2, a vertical section through the universal joint; Fig. 3, a horizontal section on line $x-x$; Fig. 4, a view representing the curtain or canopy.

In these drawings, A represents a bracket 40 firmly screwed to the side of the state-room, and projecting therefrom at right angles. To this bracket is rigidly attached the upper chamber or socket, B, of the universal joint, which is constructed as described in my former application. The chamber is rounded internally, and at the bottom has an annular groove adapted to contain a row of anti-friction balls, as shown. Loose within this case is a segment of a sphere, B', to which is attached a rod, the

lower curved surface of the segment bearing 50 on the balls, and the rod projecting out through an opening in the bottom of the chamber B. This opening may be of any size in order to permit free movement of the segment within the case, and to prevent the possibility of cramping. 55

Suspended from the chamber and bracket described, by means of the connecting-rod 2, is a precisely similar socket or chamber, D, having a corresponding annular groove and row 60 of balls. This chamber is held in reverse position by a segment, E, similar to that before described, attached to the rod 2, so that either a rotary or oscillatory motion will be permitted the chamber. The chamber D has a plane or 65 flat lower surface, and to this is rigidly secured the frame to which the swinging berths are attached. This frame is represented at F, and consists of a plate, 4, secured to the chamber D, a pair of upwardly-bent arms, 5 6, a similar pair, 7 8, extending downward, and suitable braces, as at 9, to give additional strength. The ends of the arms 5 6 are hooked, as shown, and from these hooks is suspended the upper 70 berth, G, by a pair of eyes. This permits a free lateral swing to the berth. The lower berth is suspended from hooks 11 12 on the arms 7 8 below the joint. Elastic cords 13 14 may be provided, if desired, for steadyng the 75 berth.

It will be observed that both berths are suspended from a common intermediate point by a common frame or support, and that by virtue of their position they balance one another, while they are permitted a universal movement by the joint. This is the distinguishing 80 feature of my invention.

The second part of my invention relates to a canopy or curtain for enveloping the berths and preventing the occupants from observing 85 the movement of the state-room. A frame composed of light metallic rods 20 21 is secured to the upper ends of arms 5 6, and these rods are bent outwardly, so that the canopy may hang vertically and clear the upper berth. 90 A horizontal rod, 22, connects the arms 5 6 near their lower end. The canopy is secured to the rear side of the lower berth at points 95

marked *x x*, and is supported on the frame so as to hang down in front, it being divided in front, so as to permit it to be withdrawn toward each side. The lower curtain slides on rings 5 on the rod 22, and is centrally divided.

In my former application my invention was described as applicable to swinging pens for transmitting stock and a construction of single swinging pen was described and shown 10 therein. The present invention is equally applicable to stock-pens as to berths with slight modifications, an upper and lower pen being hung from a single universally-jointed support, and arranged so as to counterbalance one another.

Having thus described my invention, what I claim is—

1. The combination, with a fixed bracket and a universally-jointed support carried 20 thereby, of a suspended frame carrying an upper and a lower berth, said bracket being between the said upper and lower berths, substantially as described.

2. A supporting-frame having upwardly and downwardly projecting arms, a berth pivoted upon the upperarms, and a second berth pivoted upon the lower arms, and a bracket intermediate between said berths fixed to suitable support, and suitable flexible connections between the frame carrying the arms and said bracket, 25 substantially as described.

3. The combination, with the cases or sockets containing the connected spherical segments and the ball-bearings, of the frame attached to the lower socket, and composed of upwardly-elevated arms 5 6, supporting a swinging upper berth, and downwardly-projecting arms 7 8, supporting a similar lower berth.

In testimony whereof I have signed my name to this specification in the presence of two sub- 40 scribing witnesses.

ALBION P. BICKMORE.
